UNITED STATES PATENT OFFICE.

HARVEY F. CRAWFORD, OF BROCKTON, MASSACHUSETTS.

SHOE SHANK-PIECE.

1,359,036.

Specification of Letters Patent. Patented Nov. 16, 1920.

Application filed December 26, 1918. Serial No. 347,514.

To all whom it may concern:

Be it known that I, HARVEY F. CRAWFORD, a citizen of the United States, residing at Brockton, in the county of Plymouth and State of Massachusetts, have invented new and useful Improvements in Shoe Shank-Pieces, of which the following is a specification.

This invention relates to a shank piece adapted to be interposed between the inner and outer soles of a shoe, to stiffen and impart the desired form and bulk to the shank portion of the shoe bottom, the shank piece being composed of leatherboard and a sheet metal stiffener superimposed on the filler and united thereto.

The object of the invention is to provide an improved union between the stiffener and the filler adapted to be formed by a single operation, and at a minimum expense.

The invention consists in the improvements which I will now proceed to describe and claim.

Of the accompanying drawings forming a part of this specification,—

Figure 1 is a top plan view of a shank piece embodying the invention.

Fig. 2 is a longitudinal section on line 2—2 of Fig. 1.

Fig. 3 is an enlarged section on line 3—3 of Fig. 1.

Figs. 4, 5, 6, and 7 illustrate the preferred means and mode of operation employed in uniting the stiffener to the filler, these views showing portions of the shank piece in section, and the uniting means also in section.

Fig. 8 is a perspective view of a portion of the punch hereinafter described.

The same reference characters indicate the same parts in all of the figures.

In the drawings, 12 represents a non-metallic filler, and 13 a sheet metal stiffener superimposed upon the filler. As here shown, the filler and shank piece are molded by pressure to impart a transversely arched form thereto. It will be understood, however, that the filler and stiffener may have any suitable form.

The stiffener is cut and portions of its material are displaced to form a slot 14 and two curved hooks 15 at opposite ends of the slot. The hooks are engaged with portions of the filler to confine the latter against the stiffener. The filler is also cut, and portions of its material are displaced to form a hook-

receiving slot or opening at 16. The end portions of the hooks project under portions of the filler at opposite ends of the slot 16, as shown by Fig. 2, the curvature of one hook being opposed to that of the other, 60 so that the hooks not only confine the filler against the stiffener, but also prevent independent endwise movement of the filler relatively to the stiffener.

I have successfully used, in forming the 65 union above described, the instrumentalities represented by Figs. 4, 5, 6, and 7. One of these is a base portion 18, having a slot 19, opening at the upper end of the base portion. The upper end of the base portion 70 constitutes a rest on which the filler 12 and the stiffener 13 are deposited, as indicated by Figs. 4 and 5. The other instrumentality is a plunger 20, guided in a vertical path and reciprocated by suitable power. The lower 75 end of the plunger is provided with a wedge-shaped punch 21, and the path of the movement of the plunger relative to the fixed base is such that when the plunger descends, the wedge enters the slot 19, as 80 shown by Figs. 6 and 7. The descent of the plunger from the position shown by Fig. 4, to that shown by Fig. 6, causes the wedge to cut the stiffener and at one operation form the slot 18 and the hooks 15. The punch at 85 the same time penetrates the filler 12, and thus forms the slot 16 in the filler. The slot 19 is considerably wider than the thickness of the punch 21, so that the lips 12^a formed by the cutting of the filler and the displacement of portions of its material, project into the slot 19, as shown by Fig. 7. When the plunger rises, the portions or lips 12^a 90 tend to move toward each other, as indicated by Fig. 3, and thus contract the slot 95 formed in the filler.

The stiffener is united to the filler by a single operation, which involves the placing of the filler and stiffener upon the fixed supporting portion 18, and causing the plunger 100 to descend.

In practice, two slots 14 and the accompanying hooks 15 may be formed at one operation, two supporting members and two plungers being employed.

The slot 16 in the filler is a result of the entrance of the punch 21 into the stiffener and the filler. The apex of the punch forms a transverse slit in the stiffener, thus forming the outer ends of the hooks 15, and 110

the inclined edges of the punch sheer the stiffener and thus form the longitudinal edges of the hooks. The descent of the punch bends or curls the hooks in opposite directions, and while the apex portion of the punch is penetrating the filler and partially forming the slot 16, the hooks force their way into the material of the filler and elongate the slot, so that when 10 the punch reaches the position shown by Figs. 6 and 7, the hooks project from the inner side of the stiffener into the slot, and also project in opposite directions under portions of the filler at opposite ends of 15 the slot.

It will be seen that the points of the hooks 15 are pressed into the compressible filler, and that the flexible lips 12^a closed together between the hooks, form a compressible 20 protuberance on the under side of the filler, between the hooks, and are adapted to bear on the upper surface of the sole. The hooks

15 are, therefore, prevented from indenting a sole on which the filler bears.

I claim:

A shank piece comprising a non-metallic filler of compressible material, and a sheet metal stiffener superimposed on the filler, and having portions of its material displaced to form integral hooks projecting from its inner side into the filler and curved in opposite directions, the points of the hooks being pressed into the compressible filler, the filler being provided with flexible lips closed together between the hooks, and forming a compressible protuberance on the under side of the filler between the hooks, adapted to bear on the upper surface of a sole, so that the hooks are prevented from indenting a sole on which the filler bears. 35 40

In testimony whereof I have affixed my signature.

HARVEY F. CRAWFORD.
